Antimbleff's Marr
ATTORNEY

UNITED STATES PATENT OFFICE.

HENRY W. TITUS, OF NEW YORK, N. Y.

EXERCISER.

Application filed July 10, 1924. Serial No. 725,130.

The device, the subject of this invention is of the general character of exercisers, the invention of myself and others and has for its special objects certain improvements which simplify the construction and which add to the efficiency of the device by increasing the length of its useful life and preventing the accidental breakage of certain parts, the untoward rupture of which might inflict personal injury upon the user.

In all other respects the construction and operation of this exerciser is similar to that of elastic exercisers in which the art has been well established.

The following is what I consider a good means of carrying out this invention and the accompanying drawing should be referred to for a complete understanding of the specification which follows.

In the drawing:—

Fig. 1, shows an exerciser. The figure is in elevation, partly in section.

Fig. 2, shows a handle for exercisers. This figure is in elevation, partly in section.

Fig. 3, shows the construction of a handle for progressive exercisers. This figure is in elevation and fractured section.

Similar reference numerals indicate like parts in all the figures where they appear.

An exerciser of this type is usually constructed to be used by both hands simultaneously, but as the parts at one side of the device, or what might be called the right hand side of the device are duplicated at the left hand side of the device, I have shown and will describe but one side.

For each hand I provide a handle as shown at 5, secured in which is a bale or wire member 6. The handle 5 may be of wood and if so formed I will provide a metallic core 7 for the handle, for a purpose that shall appear later. This metallic core may be a piece of steel tubing forced into the handle and frictionally retained therein.

The bale 6 is formed as an oblong member having a plurality of loops formed integral therein and at the side opposite the handle, which is one of the longer sides of the oblong. The number of loops may be varied, but in the device shown in Fig. 1, I have formed five loops, as five is a number that I have adopted as a standard as shall later appear. The loops are indicated by the reference characters 8 to 12 inclusive.

The wire from which the bale 6, is con-

structed, should be stiff and I prefer a steel wire. The ends of the wire are turned toward each other and are inserted into the tubular member 7, as indicated at 13 and 14.

Secured in each of the loops 8 to 12, or in any of these loops is a spring member, one of which is shown at 15. The spring member should be quite readily attached or detached from the loops 8 to 12, so that any number of springs may be employed in the exerciser, thus the exercisers may, by commencing with a single spring be progressively advanced with the increasing strength of the user until all five springs may be employed without difficulty.

The otherwise free ends of the springs 15 may be secured to a suitable support and in Fig. 1, I show the spring engaged in one of the loops of a floor member.

The floor member is a bale or wire member provided with a plurality of loops as shown at 16 to 20 inclusive, the number of loops obviously corresponding to the number of the loops in the handle member. The ends of the floor member 21 are passed through a board 22 and are turned as shown at 23 and 24 to secure the member in the board. The person using the exerciser may stand upon the board 22 and it will be understood that at the opposite end of the board another floor member 21, plurality of springs 15 and handle is provided.

In Fig. 2, I show a handle of simple construction, the bale 25 of which is formed of sheet metal, the handle being secured by a rivet 26. This handle 27 is also provided with a metallic core 28.

As I have found in progressive exercisers that a greater number of springs are often desired and as I have found in my work that a greater number of proportionately weaker springs serve more efficiently than a lesser number of proportionately stiffer springs, I have designed the handle member shown in Fig. 3, wherein the bale 29 I form ten loops 30 to 39 inclusive, forming the loops on two different planes, one behind the other, the loops bearing uneven reference characters 31, 33, 35 and etc., being on a plane further removed from the eye as shown in the drawing than the loops bearing even numbers, 30, 32, 34 and etc. All of the loops are formed integral with the bale 29.

In this construction, the ends of the handle 40 are rounded and the ends of the core 110

member 41 project slightly beyond the wooden portion 40 of the handle and serve as a ferrule to prevent the handle binding.

It has been customary to insert the free ends of a wire bale into a wooden handle without the core 41. I have found that to do this causes the interior of the handle to wear to a great extent, thus weakening the handle and causing it to become loose on the bale. 10 Occasionally handles so weakened have broken and have caused injury to the hand of the user. It is to overcome this disadvantage that the cores as shown at 7, 28 and 41 are provided.

15 It will be understood that the handle here shown may be used with wall exercisers or with chest expanders or with wrist and grip developing devices and that other modifications may be made within the scope of the

appended claim without departing from the 20 principle or sacrificing the advantages of the invention.

Having carefully and fully described my invention, what I claim and desire to obtain is:—

25 An exerciser comprising a resilient member, means for securing one end of said resilient member and a one piece handle member at the other end of said resilient member, a cylindrical metallic member of uniform 30 diameter passing through said handle and a resilient bale entering said metallic member and retained therein by the resiliency of said bale.

Signed at the city, county and State of 35 New York, this 23 day of June, 1924.

HENRY W. TITUS.
